UNITED STATES PATENT OFFICE.

GEORGE E. HERRMANN, OF MORRISTOWN, AND BENJAMIN W. TUCKER, OF SOUTH ORANGE, NEW JERSEY; SAID TUCKER ASSIGNOR TO SAID HERRMANN.

BARREL.

1,287,019.

Specification of Letters Patent.

Patented Dec. 10, 1918.

Original application filed February 17, 1912, Serial No. 678,343, (now Patent No. 1,216,807, dated February 20, 1917.) Divided and this application filed December 30, 1916. Serial No. 139,778.

To all whom it may concern:

Be it known that we, GEORGE E. HERRMANN and BENJAMIN W. TUCKER, citizens of the United States, and residents of Morristown, county of Morris, State of New Jersey, and of South Orange, county of Essex, and State of New Jersey, respectively, have invented certain new and useful Improvements in Barrels, of which the following is a specification.

This invention relates more particularly to heads and head securing means for metallic barrels.

The principal object of the invention is to provide simple and efficient means whereby the staves or members and the head or heads of the barrel may be locked together, and the ends of the barrel or container materially strengthened.

20 A further object of the invention is to provide rib-and-groove connections between the head and the ends of the staves or members.

With these and other objects in view, the invention will, hereinafter, be more particularly described with reference to the accompanying drawings, which form a part of this specification, and will be then pointed out in the claims at the end of the description.

25 In the drawings, Figure 1 is an elevation, partly broken away and partly in section, of one form of barrel or container embodying our invention;

30 Fig. 2 a plan view, partly broken away and partly in section;

Fig. 3 a detail perspective view of one of the staves or members, looking from the outside; and

40 Fig. 4 an enlarged fragmentary section showing the means for locking the staves or members and heads together.

This application is a division of our Patent No. 1,216,807, dated Feb. 20, 1917.

45 While the invention is shown as applied more particularly to a bilged metallic barrel, it will be understood that the invention is also applicable to barrels or other containers of various constructions.

50 The barrel body 10 comprises a plurality of staves or members 11. These staves or members are curved and bilged centrally to provide a barrel body which is larger at the

center than at the ends, in order that the barrel, when lying on its side, may be readily placed on its end or otherwise handled. Each stave or member 11 is provided at one edge with an inwardly extending flange 12, and along the other edge with an inwardly extending flange 13. The flange 13 is provided with a depressed portion forming a tongue or rib 14, and the flange 12 is provided with a depressed portion forming a groove 15 which is adapted to receive the rib or tongue 14 of the next adjacent stave 65 when the staves or members are assembled to form the barrel or container body. The ribs 14 and the grooved portions 15, as well as the flanges, extend the greater part of the length of the staves, and said flanges 70 extend at substantially right angles to the body portion while the tongue and groove portions lie substantially parallel with the body portion. The flanges 12 and 13 have their outer edges formed with an angular 75 portion 17 in order to prevent the sharp edge of the flange from being exposed, and this edge may be arranged at right angles to the flanges as shown, or in any other preferred manner.

80 Each flange is provided with spaced projecting portions 18 and 19. These portions are formed by forcing outwardly a part of each of the flanges 12 and 13, and the projecting portions 18 extend in one direction 85 while the projecting portions 19 extend in the opposite direction and alternate with each other so as to provide parts which project from opposite sides of the flanges. These projecting portions 18 and 19 are 90 angular in formation and have their largest portions near the body of the stave and gradually taper toward the outer edges of the flanges 12 and 13, and each projecting portion forms a groove or recess so that the 95 projecting portions of one stave may enter the groove or recessed portions of the projections of the stave next adjacent thereto when the staves are brought together. These projecting portions, by interlocking 100 as they do, prevent relative lengthwise movement of the staves or members with relation to each other, and serve further to strengthen the flanges and to assist in preventing the same from spreading or opening 105 at the joint, and serve further to assist in

locking the flanges and staves in a direction opposite to the ribs 14 and groove portions 15.

A head 20 may be located at either or both ends of the barrel or container body, and each head has its body portion 21 concaved or forced inwardly to rest against the shoulders formed by the ends of the flanges 12 and 13, the latter serving in addition to said 10 supports as strengthening ribs for the barrel body. Each head has an outwardly extending flange 22 and is adapted to be seated in a croze or groove formed by the offset portion 23 of the staves or members. 15 The flange 22 is provided with a grooved part 24 which is continuous, and said groove of each head is adapted to receive a tongue or rib 25 located at one of the ends of the staves or members 11, the said staves or 20 members, when they are put together, forming substantially a continuous annular rib around the head. A wire or other element 26 is located in the groove formed by the ribs 25 of the staves, and this wire, when 25 tightened, will serve to rigidly hold the ends of the barrel staves to the head coöperating therewith. The members or staves 11 have substantially straight outer ends 27 which lie against the flanges 22 of the heads 20, 30 and fitting about the ends of the staves and the flange of each head is a compression band or member 28. This band or member 28 has two flange portions 29 and 30, the latter being joined to the flange 28 by a 35 horizontally extending portion 31 and arranged to lie against the inner surface of the flange 22 of the head and have its inner edge resting against the outer surface of the body 21 of said head. The flange 30 may 40 be angular for a part of its length and, with the flange 28, forms an annular chamber or recess to receive the flange 22 and ends of the barrel staves. The flange 28 covers and 45 protects the tie wire 26 from injury or rupture during handling of the barrel. The band may be divided and has an offset part 32 terminating in a short skirt portion 33 which extends lengthwise of the staves or 50 members for a short distance. A wire or 55 band 34 is located under the shoulder of the band or member 28 so that when its ends are joined by twisting or otherwise, the band or member 28 may be compressed to further hold the staves or members and 60 heads together, and in such way that the band will materially assist in strengthening the ends of the barrel.

The barrel or container body may be bound intermediate the ends thereof, and for 60 this purpose various means may be employed. As shown, each stave or member is provided with a transverse groove 35 which, when the staves are put together, form substantially annular grooves around the barrel or container body. A wire band 36 is

located in each of the grooves, so that when the two bands are joined by twisting the ends or otherwise, the body will be bound intermediate the ends and thereby materially strengthened.

From the foregoing it will be seen that simple and efficient means has been provided for rigidly binding the staves or body members of the barrel to the head; that means has been provided for protecting the ends 75 of the staves from being crushed or bent; and that simple means has been provided for locking the staves and heads together to prevent relative vertical movement thereof.

It will also be seen that the wire which 80 locks the staves and head together to prevent relative vertical movement between the staves and head, is completely inclosed within and protected by the split channel member. Accidental rupture of the wire during 85 handling of the barrel is thus effectually prevented.

What I claim is:

1. A barrel or other container comprising a plurality of members, a head having an 90 outwardly extending flange provided with an annular groove, said members being provided with transversely extending ribbed portions adapted to enter the groove of the flange of the head, a wire band located in 95 the groove of the members and adapted to hold the members to the flange of the head, and means located about the ends of the members and the flange of the head for holding the several parts together, said 100 means comprising a split band provided with substantially vertical side walls, said walls being adapted to abut and bear against said head flange and ends of said members throughout their length.

2. A barrel or other container comprising a plurality of members, a head having an outwardly extending flange provided with an annular groove, said members being provided with transversely extending 110 ribbed portions adapted to enter the groove of the flange of the head, a wire band located in the groove of the members and adapted to hold the members to the flange of the head, and a divided band fitting over the 115 interlocked ends of the members and flange and covering said wire band, said divided band being of substantially inverted U-shape and having its vertical side walls bearing against said interlocked ends of the members and flange throughout their length, and means for fastening said member to the container body.

3. A barrel or other container comprising a plurality of members forming a body, 125 a head provided with a grooved flange supported within said body, said members having substantially straight portions provided with transverse ribs adapted to enter the groove of the head, a binding wire confined 130

in the groove of the members, a split band having two flanges forming a chamber to receive the flange of the head and the ends of the members and covering said binding wire, said band having an offset portion forming a shoulder, and a wire band fitting under said shoulder and adapted to com-

press the split band to bind the head, members and split band together.

In testimony whereof we hereunto affix 10 our signatures this 29th day of December, 1916.

GEORGE E. HERRMANN.
BENJAMIN W. TUCKER.
